H. H. KUNZE,
LAMP TILTING DEVICE.
APPLICATION FILED MAR. 10, 1921.

1,410,762.

Patented Mar. 28, 1922.

FIG. I.

FIG. II.

INVENTOR

H. H. KUNZE
Dr Cook & McRae & Asscs.

UNITED STATES PATENT OFFICE.

HERMAN H. KUNZE, OF MARISSA, ILLINOIS.

LAMP-TILTING DEVICE.

1,410,762.

Specification of Letters Patent. Patented Mar. 28, 1922.

Application filed March 10, 1921. Serial No. 451,418.

To all whom it may concern:

Be it known that I, HERMAN H. KUNZE, a citizen of the United States of America, and a resident of Marissa, in the county of

5 St. Clair and State of Illinois, have invented certain new and useful Improvements in Lamp-Tilting Devices, of which the following is a full, clear, and exact description, reference being had to the accompanying 10 drawings, forming a part of this specification.

My invention relates to improvements in lamp tilting devices especially designed for use on automobiles and having manually controlled means for varying the angle of the beam of light.

My object is to provide a lamp mounting, and means for moving same to vary the angle of the lamp with respect to the horizontal, 20 of simple and inexpensive construction, capable of ready installation, simple in its operation and whose operating connections, include elements which tend to prevent accidental tilting of the lamp.

25 My improvements consist in the novel construction, arrangement and combination of parts, as hereinafter fully, clearly and concisely set forth, definitely pointed out in my claims, and illustrated by the accompanying drawings, in which—

Fig. I is an elevation, partly in section, of a headlight and operating means constructed in accordance with my invention.

Fig. II is a transverse sectional elevation, 35 taken approximately on the line designated II—II of Fig. I.

Referring to the drawings, by numerals, 1 designates the side members of the chassis, shown as channel-beams, as in common and 40 each provided adjacent its forward end with holes 2, in its flanges, inside the web, for receiving the vertical stems 3 of the lamp supporting posts 4. By preference said stems 3 are threaded and provided with nuts 45 5 whereby the posts may be adjusted vertically with respect to the chassis.

Each post is provided at its upper end with a socket bearing 6 and is so shaped that said socket occupies a position both forwardly and laterally removed from the stems, and as shown in Fig. II each bearing 6 is provided with a cap 7, having a cavity for a spring 8 and a spring-tensioning device in the form of a plug 9 threaded in the 55 spring cavity.

Each bearing 6 constitutes a support for

a horizontal trunnion 10, formed preferably as an integral part of a yoke 11, shaped to embrace the lamp 12 and said yoke and lamp are secured together by the perforated ears 60 13 laterally projecting at each side of the lamp and the threaded stems 14 extending from the yoke, said stems being provided with nuts which engage the ears 13. As shown in Fig. II, I provide a pair of such 65 yokes which I preferably form integral with a horizontal rod 15, whereby the two lamps, with which automobiles are regularly equipped, may be synchronously operated upon a movement of either yoke. 70

The lamp moving means comprises a bell crank, composed of arms 16 and 17, which is mounted in a bearing 18 secured to the chassis at the rear of one of the lamp supporting posts 3, an operating rod 19, which 75 is connected with the arm 16 of the bell crank and extends to a point conveniently accessible to the operator, a spring 20 for normally holding the bell crank in the position shown by Fig. I, an adjustable abutment screw 21 80 for selectively establishing the normal position of the bell crank and a connecting rod 22 between the bell crank and one of the yokes 11.

The arm 17 of the bell crank terminates in 85 a ball 23, which is fitted in a socket bearing 24, constructed similarly to the bearings 6 and provided with a threaded bore for the reception of the threaded end 26 of the connecting rod 22. Similarly the forward end 90 of the rod 22 is connected with a ball 27 whose stem 28 is connected with a yoke 11, by means such as threads, whereby it may be vertically adjusted.

The ball 27 is located in a socket 24' provided with a spring 8^a whereby the ball is retained in engagement with its seat. 9^a designates a plug screwed into the socket 24' to provide an adjustable seat for the spring 8^a. The socket 24 is provided with a plug 9^b and spring 8^b adapted to retain the ball 23 in engagement with its seat. After the sockets 24 and 24' are properly adjusted on the threaded ends of the connecting rod 22, they may be secured through the medium of 105 nuts 30 mounted on said threaded ends and adapted to engage the respective sockets.

It is to be observed (Fig. I) that the pivotal point 17' of the bell crank, the ball 23 and ball 27 are in horizontal alinement with 110 each other, so as to normally hold the pivotally supported lamps in substantially hori-

zontal positions. Arising out of this arrangement there results a "dead center" which tends to stabilize the connection between the operating rod 19 and the pivoted lamps to the end that undesirable pivotal movements of the lamps are minimized.

By reason of the threaded stems 3 of the lamp supporting posts and the threaded stem of the ball 27 a relatively wide range 10 of adjustment is obtained in the positioning of the ball 27 at the forward end of the operating means, to preserve its alinement with the ball 23 and pivotal point of the bell crank. However, this alinement is ordinarily obtained by adjusting the screw 21 which engages the bearing 18.

The yokes 11, their connecting element 15, their supporting trunnions 10 and lamp securing means such as the threaded stems 14 20 are constructed as a unit, hence the construction is simple, strong and economical.

In the employment of bearings including springs 8, 8^a and 8^b exerting pressure on the balls, the apparatus as a whole is carried 25 with a minimum of rattle and vibration.

With the apparatus assembled as shown, it will be obvious that the lamps may be "set" to positions to cast their rays forwardly in a horizontal direction, which is desirable for 30 distant illumination but which is objectionable to pedestrians or occupants of other vehicles. Therefore, the lamps may be moved by a manipulation of the rod 19, to cast their rays at an angle to their normal carrying 35 position, and out of the direct line of the eyes of persons in advance of the automobile.

I claim:

1. In an apparatus of the class described, a post having a bearing at its upper end, a yoke supported for rocking movements upon 40 said post, a bell crank, a flexible connection between said yoke and bell crank, a spring for holding the bell crank in its normal position, a manipulative element connected with the bell crank, and means for adjusting 45 said connection to aline its points of flexure.

2. In an apparatus of the class described, a pair of connected yokes, a lamp supported in each yoke, trunnions carried by said connected yokes, posts having bearings for said 50 trunnions, a bell crank, a manipulative element for the bell crank, a spring for normally holding the bell crank in its normal position, a jointed connection between said connected yokes and bell crank, and means 55 for adjusting the connection to locate its joints in alinement with each other.

3. In an apparatus of the class described, a pair of connected yokes, a lamp supported in each yoke, trunnions carried by said connected yokes, posts having bearings for said 60 trunnions, a bell crank, a manipulative element for the bell crank, a spring for normally holding the bell crank in its normal position, a jointed connection between said 65 connected yokes and bell crank, and means for adjusting the connection to locate its joints in alinement with each other, the joints of said connection comprising balls and sockets and springs bearing on said 70 balls.

In testimony that I claim the foregoing I hereunto affix my signature.

HERMAN H. KUNZE.
